ELECTROMAGNETIC DEVICE

George Atchison, Jersey City, and Charles V. Nichols, Montclair, N. J., assignors to Western Electric Company, Incorporated, New York, N. Y., a corporation of New York

Application March 31, 1931, Serial No. 526,756

2 Claims. (Cl. 177—329)

This invention relates to electromagnetic devices, and more particularly to electromagnetic signaling devices.

In devices of this character it has been found, in some instances, that the magnetizing force necessarily employed in order to insure the positive actuation of the armature or moving element, produces magnetic saturation of the core or pole piece, so that when the magnetic force is removed, the armature tends to stick or adhere to the pole piece due to residual magnetism.

An object of the present invention is to insure the quick and positive release of the moving element or armature from the magnetic pole piece of an electromagnetic device upon cessation of the magnetizing force.

This object is attained in accordance with a feature of the present invention by tensioning the armature or moving element of the device while the armature is attracted by the pole piece and utilizing this tension to expedite the release of the armature from the pole piece upon cessation of the magnetizing force. In accordance with one embodiment of the invention, the resilient display shutter carried by the armature of an electromagnetic signaling device is caused to engage a stop strip while the armature is attracted by the pole piece, the stop strip being arranged to slightly flex the resilient shutter and thereby introduce a predetermined tension therein. This tension insures the quick and positive release of the armature upon cessation of the current flow through the operating coil of the device.

The invention will be clearly understood from the following detailed description when read in conjunction with the accompanying drawing, in which

Fig. 1 is an elevational view, partly in section, of an electromagnetic signaling device embodying the features of the invention, and

Fig. 2 is a fragmentary bottom plan view of a bank of devices of the type shown in Fig. 1.

Referring to the drawing, the numeral 10 indicates a portion of a mounting which is made of suitable dimensions to accommodate a plurality of electromagnetic signaling devices 12 arranged side by side as shown in Fig. 2. A designation strip holder 13 and a face plate 14 are mounted in any suitable manner on the front face of the mounting 10, a transparent celluloid strip 15 being interposed between the mounting and the face plate. The holder 13 is so formed as to permit the insertion of and retain in place a designation strip 16.

Each signaling device 12 consists of an operat-

ing coil or winding 17 having a core 18 extending axially therethrough and projecting from either end thereof. Attached to one end of the core 18 is a rear angle pole piece 20 and attached to the opposite end of the core is a front angle pole piece 21 to which is adjustably secured an auxiliary pole piece 22. The rear face of the mounting is notched or slotted to accommodate the front pole piece 21, whereby the signaling device is rigidly secured to the mounting by a single screw 24 threaded in the end of the core 18.

An armature 25 is pivoted at one end upon a pin 26 carried by the rear pole piece 20. Adjustably secured to and extending from the free end of the armature is a member 28 consisting of a strip of resilient material, preferably nickel silver. The front end of the member is provided with a flange forming a display shutter 29 which has its front face colored so that when the shutter assumes its actuated position, as shown in Fig. 1, the colored face will appear before an aperture or slot 30 in the face plate 14 and will be readily noticeable to the operator through the transparent celluloid strip 15, there being an aperture 30 in the face plate for each signaling device 12.

A pin 32 depending from the auxiliary pole piece 22 extends through a slot 33 in the shutter 28. This pin serves to prevent side movement or displacement of the shutter. The lower edge of the face plate 14 is bent inwardly to provide a shelf or ledge 34 for supporting the shutter when in its normal or unactuated position, as indicated in dotted lines in Fig. 1.

In accordance with a feature of the present invention, means is provided for insuring the quick and positive release of the shutter 28 upon the cessation of the operating current through the operating coil 17. This means comprises a shutter stop strip 36 having an inwardly extending flange 37 formed in its lower edge for engaging the flanged outer end of the shutter as the latter approaches its actuated position. The stop strip 36 is secured to the front face of the mounting 10 and is of sufficient length to serve all of the devices 12 carried by the mounting.

Non-magnetic stop pins 50 are secured to the armature 25 to limit the upward movement of the armature 25 and to prevent the armature 25 from contacting with the front pole piece 21 if the current through the operating coil at any time reaches an amount sufficient to overcome the tension in the member 28.

The operation of the device is as follows:—The normal position of the member 28 is shown in

dotted lines in Fig. 1. When the shutter is in this position, its colored face is not visible through the slot 30 in the face plate 14. Upon the energization of the operating coil 17, the armature 25 and member 28 are attracted by the pole pieces 21 and 22, whereby the flanged end 29 is moved upwardly to a position wherein its colored face is visible through the slot 30. Upon arriving at this position, the flanged end 29 engages the flanged lower edge 37 of the stop strip 36, whereby continued movement of the armature toward the attracting pole piece causes the member to be flexed sufficiently to introduce a predetermined tension therein. This tension serves to overcome the tendency of the armature to stick or adhere to the attracting pole piece after the operating current is discontinued, thereby insuring the quick and positive release of the shutter.

It is to be understood that the embodiment of the invention herein illustrated and described is merely illustrative of one particular application of the invention which is capable of numerous other applications within the scope of the appended claims.

What is claimed is:

- 25 1. In an electromagnetic signalling device, a core having a winding thereon, front and rear pole pieces secured to said core, each of said pole pieces having a portion thereof extending beneath said core in a direction parallel thereto, a pin attached to the parallel portion of the rear pole piece, an armature having an aperture through one end thereof through which said pin extends, resting on said rear pole piece, extending parallel to said core beneath said front pole piece, and 30 adapted to be moved upward toward said front 35

pole piece when said winding is energized, a non-magnetic stop pin secured to said armature to limit the upward movement of the armature toward said front pole piece, a non-magnetic resilient member attached to the other end of said armature and having integral therewith a visual signal element comprising a flange located forward of said front pole piece, a member secured to said front pole piece having a window portion through which said visual signal flange is visible when the armature is attracted toward the front pole piece and a flange portion which forms a stop member for the armature in its non-display position and means contacting with said flange when said armature is moved upward for tensioning said resilient member.

2. In an electromagnetic signaling device, a core having a winding thereon, front and rear pole pieces secured to said core, a gravity return armature movably mounted therebeneath on said rear pole piece and movable upward toward said front pole piece when said winding is energized, a resilient member carried by said armature and having an upwardly projecting flange forward of said front pole piece and forming a display shutter, a member supported by said front pole piece having a window portion through which the shutter is visible when the armature is attracted toward the front pole piece and also having a flange portion which forms a stop member for the shutter flange in its non-display position, and means contacting with said shutter flange when said armature is moved upward for tensioning said resilient member.
